INSULATING INSERT FOR A BUILDING BLOCK OR THE LIKE

David Nickerson, Wilbraham, Mass., assignor to
Korfil, Inc., Chicopee, Mass.

Filed Jan. 27, 1975, Ser. No. 544,666

Term of patent 14 years

Int. Cl. D25—01

U.S. Cl. D25—98

FIG. 1

FIG. 2

FIG. 3

FIG. 4

FIG. 5

FIG. 6

FIG. 7

FIG. 1 is a perspective view of an insulating insert for a building block or the like showing my new design;

FIG. 2 is a side elevational view;

FIG. 3 is a side elevational view showing the side opposite that seen in FIG. 2;

FIG. 4 is a top plan view;

FIG. 5 is a bottom plan view;

FIG. 6 is a rear elevational view; and

FIG. 7 is a front elevational view thereof.

I claim:

The ornamental design for an insulating insert for a building block or the like, as shown and described.
